Primary Examiner — Catherine A Tuttle(57) **CLAIM**

The ornamental design for the punt trainer, as shown and described.

DESCRIPTION

FIG. 1 is a front-top perspective view of the punt trainer showing my new design;

FIG. 2 is a front-bottom perspective view thereof;

FIG. 3 is a rear-top perspective view thereof;

FIG. 4 is a rear-bottom perspective view thereof;

FIG. 5 is a front elevational view thereof; the rear elevational view being mirrored thereto;

FIG. 6 is a left elevational view thereof;

FIG. 7 is a right elevational view thereof;

FIG. 8 is a top plan view thereof;

FIG. 9 is a bottom plan view thereof; and,

FIG. 10 is a front-top perspective view as in FIG. 1 but showing the punt trainer extended.

The broken lines in FIGS. 1-7 and 10 are included for the purpose of illustrating adjustment holes that form no part of the claimed design.
